ELECTRIC HAMMER

Pietro Aurelio Macchioni, Turin, Italy, assignor
to Soc. An. S. I. M. B. I., Turin, Italy

Application December 27, 1938, Serial No. 247,962

1 Claim. (Cl. 172—126)

This invention relates to reciprocating electric hammers of the type comprising a solenoid enclosed in a casing of magnetic material and a movable core to which is imparted a reciprocating motion by the magnetic pull and reaction of an opposing spring.

An object of this invention is to provide an electric hammer of the type referred to above, in which the magnetic casing is constituted by sheet metal punchings radially arranged about the hammer axis so as to form a cage enclosing the coil. The outer edges of the punchings are curved to a channel form to interlock one another, and the punchings are clamped between two end plates by means of bolts extending through the punchings. With this arrangement numerous electromagnetic paths are formed, eddy currents are avoided and the internal hammer parts are efficiently cooled by reason of the large air-exposed surface of the casing.

A further object of this invention is to provide an electric hammer, in which the punchings forming the casing are arranged to form stackings with their channel-shaped portions in interlocking engagement, said stackings being arranged about the coil with the concavity of the channel of a stacking facing the concavity of the channel of the adjacent stacking, so as to form conduits through which bolts clamping the stackings between end plates extend, this resulting in a compact shock-proof casing, through which cooling air freely circulates.

A further object of this invention is to provide an electric hammer of the type above referred to, in which the movable core is guided at its ends in a hole in a counter-core and in a hub adapted to receive the tool, respectively, so as to avoid frictions between the movable core and the spool on which the coil is wound.

The above and further objects will be clearly understood from the following description referring to the accompanying drawing, in which:

Figure 1 is a longitudinal section, and

Figure 2 is a cross section on an enlarged scale.

Referring to the drawing, 1 denotes the coil wound on a spool 2 of insulating material, seated in the inner recess of an annular cage formed by punchings 3 radially arranged and curved near their outer edge to form a channel 4. The punchings are grouped to stackings a, b, c . . . , with interlocking channel-shaped portions 4, and the stackings are arranged with the concavity of the channels of one stacking inverted with respect to the channels of adjacent stackings, so as to form at the periphery of the cage equidistant

conduits 5, that are utilized as passages for the bolts 6 clamping the cage between the end plates 7 and 8, respectively.

It will be apparent that with this arrangement a strong magnetic shell is obtained, unaffected by the strong vibrations to which the hammer is subjected in operation.

The shell has fitted therein at one end a counter-core 9 provided with a flange 10, by means of which it rests on the punchings, and having an axial bore enlarged at one end for receiving the disc 11 abutted by a powerful spring 12 and lined on its remaining portion by a bushing 13 serving as a guide for a shaft 14 connected to the movable core 15 having at its opposite end an extension 16 guided in its axial movement in a bushing 17 integral with the hub 18 screwed to the plate 8.

The movable core 15 rests on a volute spring 18 seated in an annular recess in the hub 18 and adapted to absorb shocks, avoiding transmission thereof to the shell.

With the above described arrangement the movable core 15 is guided in its movement at both ends by means of the shaft 14 and the extension 16, safely avoiding any friction between the core and the spool 2 and undue wear and jamming.

Both the counter-core 9 and the core 15 are formed by radially arranged punchings of magnetic metal, tightly clamped together and welded at their ends to clamping rings so as to form outside the magnetic field compact cylindrical shock-proof blocks. This construction considerably reduces losses by eddy currents.

The spool is resiliently held in position in its seating by means of small springs 20 arranged in the inner recesses 20' between the stackings a, b, c, . . . having small insulating spacers fitted therein, and held against the spool 2 by means of the plate 8.

The plates 7 and 8 are provided on their inside face with circular grooves receiving the tongues 22 of the punchings and on its outside the plate 7 has a flange 23 forming a box, enclosing an insulating disc 24 carrying a stationary contact plate 25 connected to a terminal of the coil 1. A spring plate 26 connected to one of the wires of the lead-in cable 27 is provided with a contact co-operating with the contact of the stationary plate 25. The other conductor of the cable 27 is grounded by means of the screw 28 to the plate 7.

The flange 23 has secured thereto diametrically opposed brackets 29 and 30, to one of which is hinged the cover 31 having a handle 32, while the other bracket has pivotally attached thereon a

bolt 33 provided with a winged nut for clamping the cover 31 on the plate 7. The cover has centrally screwed therein an adjusting plug 34 for the spring 12 and a button 35 is arranged in a branch of the handle. The button 35 acts through the spring 36 and the push-rod 37 to move the plate 25 into engagement with the plate 26 so as to close the circuit energising the coil.

10 Use of the hammer is extremely simple. The cable is connected to an alternating current source and the tool 38 is fitted into the hub 18, whereupon the button 35 is depressed, thereby closing the circuit energising the coil 1. The 15 movable core 15 is normally held by the spring 12 against the shank of the tool. As the coil is energised the core is drawn inwardly, compressing the spring 12. In passing from a positive to a negative alternation and vice versa the current drops to zero and the spring 12 violently pushes the core outwardly thereby imparting a 20 blow to the tool.

The core strikes in a minute a number of blows equal to the number of alternations of the current. By adjusting the resilient reaction of the big spring 12 or of the shock absorbing spring 19, the effect of blow may be reduced.

In operation the extension 16 on the movable core acts as a piston and generates air currents 25 which, by flowing along the movable core and

filtering between the spool and core and counter-core and between the punchings of the shell, efficiently cools the inner parts of the hammer. The dissipation of heat is further improved by the form and arrangement of the punchings of 5 the shell.

What I claim is:

An electric hammer comprising, end plates, a magnetic shell arranged between said end plates and constituted by punchings radially arranged 10 about the hammer axis and curved to a channel form near their outer edge, said punchings being grouped to form stackings with the channel-shaped portions in interlocking engagement, said stackings being arranged in such manner that 15 the concavity of the channels of a stacking is inverted with respect to the concavity of the channels of adjacent stackings so as to form longitudinal conduits in proximity to the outer periphery alternating with longitudinal recesses 20 in proximity to the inner periphery of the shell, an energizing coil seated in an annular groove formed in the inside face of said shell, spring means in said recesses pressed between said coil and one of the end plates to oppose the vibrations 25 of the coil, and bolts in said conduits to clamp the shell between said end plates and form a rigid vibration resisting unit.

PIETRO AURELIO MACCHIONI. 30
